ARTICULATED CAR

William H. Mussey, Chicago, Ill., assignor to Pullman-Standard Car Manufacturing Company, Chicago, Ill., a corporation of Delaware

Application March 16, 1935, Serial No. 11,453

5 Claims. (Cl. 105—4)

This invention relates to cars of the type that have adjacent ends of two car sections or bodies borne on a common truck, popularly called articulated cars, or trains, and the principal object 5 is to give the two car ends supporting bearings of substantially the same area presented in like relation about a common center on the truck.

Further objects and advantages of the invention will appear as the disclosure proceeds and 10 the description is read in connection with the accompanying drawings in which

Fig. 1 is a side elevation of the adjacent ends of two car bodies and a common truck;

Fig. 2 is a perspective view of portions of two 15 end sills, two center plate brackets, and part of the common truck displaced to indicate the manner of assembly;

Fig. 3 is a perspective view of one of the center plate brackets;

20 Fig. 4 is a perspective view of the same center plate bracket from a different point of view;

Fig. 5 is a perspective view of the other center plate bracket;

Fig. 6 is a longitudinal section through the 25 parts shown in Fig. 2 in their assembled relation;

Figs. 7 and 8 are sectional views taken on the lines 7—7 and 8—8 of Fig. 6.

But these specific views and the corresponding 30 description are used to illustrate the best embodiment so far made and not to define the limits of the invention, which is susceptible of many other embodiments.

In Fig. 1, 10 and 11 indicate adjacent ends of the car bodies supported on a common truck 12, 35 of the swing motion type, including a bolster 13 equipped with a depressed center plate 14, having a flat bearing surface 15 from which rises a cylindrical wall 16. The bolster and the center plate are made in separate castings fitted one 0 within the other, and made fast by bolts 17 extending through the flange 18 of the center plate into the sides 19 of the truck bolster. The depression is made in an effort to get the flat bearing surface 15 substantially in line with the axle 5 of the truck.

Each car body includes an end sill 20, or 21, to which is secured a center plate bracket 22, or 23, by means of bolts 24, a key 25 and a dowel 26.

The center plate bracket 23 has a flat supporting bearing surface to rest upon the flat surface 15 of the body center plate, and comprises two laterally spaced parts 27 and a lengthwise centrally placed part 28, whereby the body is given a wide base in a sort of three-point support.

The bracket 22 also has a flat supporting bear-

ing surface composed of two laterally spaced parts 29 and a lengthwise centrally placed part 30, which interfit with the corresponding parts on the bracket 23, as shown in Figs. 6, 7 and 8, the part 30 being on an arm 31 which, in assembly, 5 passes through the opening 32 in the bracket 23. The several parts of the composite center bearings are spaced apart, as shown in Figs. 7 and 8, indicated by the gaps 33, to provide for the relative rotary movement about the common center 10 34, as the car passes around a curve in the track. The outside surfaces of the center plate parts are rounded to correspond with the cylindrical wall 16 of the truck center plate within which they fit with about 1/64" clearance.

The clearance between the curved heel 35 on the bracket 22 (Fig. 5) and the corresponding surface 36 on the bracket 23 (Fig. 4) is slightly in excess of $\frac{1}{32}$ " in this embodiment to make possible the transfer of draft strains from one car 20 to another through the truck center plate.

The two heads 37 and 38 on the end sills, into which the dowels 26 are received, are spaced about $\frac{1}{16}$ " when the car is on level track and this allows sufficient clearance for taking the valleys on 25 standard railways and the buff strains are ordinarily transferred from one car to another through the truck center plate.

While side bearings or a stabilizing rigging will 30 ordinarily be used, it has been found that giving the car bodies a relatively wide flat support, or base, on the truck center plate tends to eliminate swaying and makes for smooth comfortable riding.

This invention enables such a support to be 35 given the two adjacent car ends without extending the width of the bolster to troublesome dimensions, or spacing the car ends an undesirable distance apart.

It also makes an interlocked articulated joint 40 between the car ends that resists separation lengthwise and climbing of one car section on the other.

The car bodies, or sections, can be separated easily by raising the section at the left in Fig. 6 45 a little more than the depth of the center plate and then moving it longitudinally of the car. The opening 32 in the bracket 23 has a sufficient vertical dimension to allow this operation.

I claim as my invention:—

1. In an articulated car, adjacent car ends, a common truck, a center plate on the common truck having a bearing surface, and supporting bearings for the car ends each having several bearing surfaces resting on said center plate, the 55

major portions of all of said several bearing surfaces being spaced apart and being substantially equidistant from a common center.

2. In an articulated car, adjacent car ends, a common truck, a center bearing member on the truck, and supporting bearings for the car ends resting on the center bearing member, each supporting bearing including two bearing parts spaced laterally on opposite sides of a bearing part of the other supporting bearing.

3. In an articulated car, adjacent car ends, a common truck, a center bearing on the truck, a supporting bearing member for each car end resting on the center bearing, each member including two bearing parts spaced laterally on opposite sides of a single bearing part of the other member, one of the members having an opening therethrough between its said two bearing parts through which said single bearing part of the other member may be inserted or removed.

4. In an articulated car, adjacent car ends, a common truck, a center bearing on the truck, supporting bearing members for each car end resting on the bearing, each member including

two bearing parts spaced laterally on opposite sides of a single bearing part of the other member, one of the members having an opening therethrough between two of its bearing parts through which opening the single bearing part of the other member positioned between said two bearing parts may be withdrawn to separate said car ends.

5. In an articulated car, adjacent car ends, a common truck, a center bearing on the truck having a depressed, uni-planar bearing surface and a vertically rising cylindrical wall surrounding said bearing surface, supporting bearing members for each car end resting on the bearing surface, each member including two bearing parts spaced laterally on opposite sides of a single bearing part of the other member, one of the members having an opening therethrough between two of its bearing parts through which opening the single bearing part of the other member positioned between said two bearing parts may be lifted to separate said car ends.

WILLIAM H. MUSSEY.
